UNITED STATES PATENT OFFICE.

LOUISE F. SPOERR, OF BROOKLYN, NEW YORK.

COLLAPSIBLE RECEPTACLE.

1,208,040.

Specification of Letters Patent. Patented Dec. 12, 1916.

Application filed November 4, 1915. Serial No. 59,588.

To all whom it may concern:

Be it known that I, LOUISE F. SPOERR, a citizen of the United States, residing at Brooklyn, in the county of Kings and State 5 of New York, have invented certain new and useful Improvements in Collapsible Receptacles, of which the following is a full, clear, and exact specification.

This invention relates to collapsible or 10 knockdown receptacles, and has for its object to produce an improved receptacle of this kind which is especially useful as a chamber or toilet vessel and which may be conveniently carried in traveling on account 15 of its capability of being collapsed sufficiently to be placed in a suit case.

Another object is to provide a sectional receptacle which when in erected position is self supporting, no separate supporting 20 means being required.

A further object is to provide a sectional receptacle with a sanitary but inexpensive lining which may be destroyed after being used, leaving the receptacle itself unsoiled.

25 It is also the aim of the invention to provide for protecting or covering the upper edge or rim of the lining when in place in the erected receptacle so that the space between the lining and the inner wall of the 30 receptacle is closed against the entrance of foreign matter which would soil the receptacle proper.

Other objects will appear as the description proceeds.

35 The invention will be first hereinafter described in connection with the accompanying drawings, which constitute a part of this specification, and then more specifically defined in the claim at the end of the 40 description.

In the accompanying drawings, wherein similar reference characters are used to 45 designate corresponding parts throughout the several views: Figure 1 is a central vertical sectional view of a collapsible receptacle constructed in accordance with my invention, the same being in erected position with the sanitary lining in place, and Fig. 2 is a similar section of the receptacle 50 as it appears when folded or collapsed.

The receptacle is made in a plurality of sections, preferably three, the bottom section 1 being pan-shaped and the upper sections 2 and 3 being in the form of rings.

The walls of the sections are inclined so as 55 to form continuations of one another when the receptacle is erected, as illustrated in Fig. 1, and permitting section 1 to be placed in section 2 and section 2 in section 3 when the receptacle is collapsed, as shown in 60 Fig. 2.

The upper edge of the bottom section 1 is provided with an outwardly turned flange 10 having a groove 11 opening upwardly and terminating substantially in the plane 65 of the rim of the wall of the section. The middle section 2 has an outwardly and downwardly bent flange 20 around its lower edge to rest upon the rim of the lower or bottom section 1 and fit in the groove 11 in 70 the flange 10 on said bottom section. Around the upper edge of the middle section there is a flange 21 formed like the flange 10 and having a groove 22 similar to the groove 11. The top section 3 has a flange 30 at its 75 lower edge similar to the flange 20 and adapted to rest upon the upper edge or rim of the middle section and fit in the groove 22 when the receptacle is erected. At its upper edge, the top section 3 is bent inwardly to 80 form a rounded bead 31 overhanging the wall proper of said section and open at its bottom, as at 32, said opening being in line with the inner surface of the wall of the receptacle.

85

It is obvious from Fig. 1 how the sections are placed on one another in erecting the receptacle. Before the top section is put in position on the middle section, a paper or other sanitary lining 4 is placed in the receptacle, and in subsequently placing the top section in position the rim of the lining is inserted through the opening 32 into the bead 31, as will be readily understood. After use, the top section is first removed, 95 the lining then removed and destroyed, and the middle section finally taken off of the bottom section and the three sections of the receptacle nested as shown in Fig. 2, when they may be conveniently packed in a suit 100 case.

It will be noted that the overhanging bead 31 on the top section of the receptacle effectively covers the rim of the lining and prevents foreign matter from entering between said lining and the inner surface of the wall of the receptacle, to the end that the receptacle is kept clean or unsoiled.

105

Having thus described my invention, what I claim as new and desire to secure by Letters Patent of the United States is:—

5 A collapsible receptacle comprising a lower section having means at its upper edge for supporting an upper section, an upper section having an inwardly overhanging bead with an opening in its bottom in line

with the inner surface of the wall of said upper section, and a continuous cup-shaped 10 lining to fit throughout the sections when erected and have its rim extend into said overhanging bead for the purpose specified.

In testimony whereof I have signed my name to this specification.

LOUISE F. SPOERR.
